DESIGN FOR A COMBINATION DICKEY SCARF

Howard J. Levi, New York, N. Y.

Application July 4, 1942, Serial No. 107,422

Term of patent 3½ years

To all whom it may concern:

Be it known that I, Howard J. Levi, a citizen of the United States of America, residing in New York city, county of New York, and State of New York, have invented a new, original, and ornamental Design for a Combination Dickey Scarf, of which the following is a specification, reference being had to the accompanying drawings, forming part thereof.

Fig. 1 is a front view of a combination dickey scarf showing my new design.

Fig. 2 is a rear view thereof.

Fig. 3 is a front view of the combination dickey scarf shown in Fig. 1, illustrating the ends in tied position.

Fig. 4 is a rear view of Fig. 3.

I claim:

The ornamental design for a combination dickey scarf, substantially as shown.

HOWARD J. LEVI.
